UNITED STATES PATENT OFFICE.

EDGAR WEBSTER SUMMERS, OF PITTSBURG, PENNSYLVANIA.

HOPPER-CAR.

No. 918,390.

Specification of Letters Patent.

Patented April 13, 1909.

Application filed October 14, 1908. Serial No. 457,678.

To all whom it may concern:

Be it known that I, EDGAR WEBSTER SUMMERS, a resident of Pittsburgh, in the county of Allegheny and State of Pennsylvania, have invented a new and useful Improvement in Hopper-Cars, of which the following is a specification.

This invention relates to that class of cars having discharge openings in their bottoms, 10 and more particularly to hopper bottom cars for carrying and discharging iron ore and similar materials.

In my application filed September 22, 1908, Serial No. 454,244, I have illustrated, de- 15 scribed and claimed an ore car of standard length, having in its bottom a discharge opening of such size as to prevent the bridging of the ore and insure discharge of the load, and closed by a pair of longitudinally ar- 20 ranged doors.

The present invention is an improvement on the car described in said application, and has for its objects to improve the sloping end door portions so as to prevent the lading 25 from choking and bridging when it slides down to the discharge opening; to improve the body bolster construction in order to effectively take care of the stresses and also to permit ready access to the space between 30 said bolsters and the sloping end floors; to provide a horizontal web girder secured to the draft sills for transmitting buffing and tugging stresses to the car sides, and used in conjunction with an elevated platform so ar- 35 ranged as to prevent lodgment of ore on said web girder; and other improvements which will be hereinafter described and claimed.

In the accompanying drawings, Figure 1 is a plan view of a portion of the car with 40 parts broken away and the discharge doors omitted; Fig. 2 is a central vertical longitudinal section through the same; Fig. 3 is an end view of the car; Fig. 4 is a transverse section, the left hand portion being taken 45 outside of the bolster and the right hand portion being taken centrally through the hopper; Fig. 5 is a vertical transverse section on the line 5—5, Fig. 2; and Fig. 6 is a detailed transverse section through a modified 50 form of top chord for the car sides.

The car is of the hopper type, having plate girder side walls extending for the full length of the body and having firmly secured to their ends the web plate 2 of the body bolster. 55 These side walls are provided at their upper edges with a suitable cord 3, and their lower

portions are formed by a separate plate 4 which projects down to the underframe level and is then turned inwardly, as at 5, to support the lower edges of the inclined side hopper sheets 6. Discharge opening 7 occupies the space transversely of the car between the side hopper sheet 6 and is somewhat wider than the track, as shown in Fig. 1, and extends longitudinally of the car for a distance 60 greater than that between the inner truck wheels. This discharge opening is closed by a pair of longitudinally arranged doors 8 hinged at the sides of the car 9, and closing toward the center of the car, being closed by 65 means of winding chains 10 passing over guide sheaves 11 and onto drums on winding shaft 12 mounted transversely of the car. The draft sills 13 extend inwardly beyond the body bolster and at their inner ends are 70 connected by gusset plates 14 to the end sloping floor plates 15.

The car so far described, except for the shape of the end sloping floor plates, is substantially the same as that of my applica- 75 tion above identified.

The sloping floor plates have their side portions, as at 16, sloping upwardly, viewed transversely of the car, and secured to the side walls by means of rivets 17. The portions 16 are on substantially the same angle as the sloping side hopper plates 6, and extend inwardly to a line coincident with the side edges of the discharge opening; that is, side portions 16 of the floor plates are of sub- 80 stantially the same width as the sloping side hopper plates 6. These side portions 16 act as confining walls for the lading, and the space between the same is of substantially the same cross section from the outer upper end of 85 the end floor plates to the discharge opening, so that as the lading slides down the end floor plates to the discharge opening it does not need to change its cross sectional area, as is the case where the sloping end floor and sloping side hopper plates meet on a bias or diagonal line, as is the common practice. Consequently, the liability of the lading choking and bridging as it reaches the discharge 90 opening is practically overcome, and the free 95 discharge of the load is assured.

A horizontal web girder 20, consisting of one or more plates, is secured to the lower edges of the end floor plates, as at 21, and at this point is also placed a transverse reinforcing plate 22. The horizontal web girder 100 is secured at its side edges to the plate girder

side walls of the body, and serves to transmit the buffing and tugging stresses to said side walls. The outer end of said web girder is tapered, as shown in Fig. 1, and has flanged edges at 23.

At the end of the overhanging portion of the body is the end plate 24, and an elevated platform 25 is also provided in order to permit the train men to traverse a loaded train. 10 Ladders 26 lead downwardly from each side of the elevated platform. The portion of the horizontal web girder which projects beyond the overhanging end of the body is of less width transversely than the elevated platform 15 form 25, as is apparent from Fig. 1, so that any ore which is spilled from the shovels in loading the car, can find no lodgment at the end of the car except on the elevated platform. The spaces 27 underneath the ladders 20 and inclosed by the end sill 28 and end side sill member 29, are open, and the rungs of the ladder are small so that the ore will not lodge on the same so that it is necessary to clean off only the elevated end platforms. 25 This materially reduces the amount of labor at the mines in cleaning the car before taking the same out of the pit. This is of advantage, as the grade of ore in different parts of the same mine varies, and as the blending or 30 mixing of the ore is started at the mines, the operators are careful not to get even small quantities of ore from one part of the mine into another, and go to considerable trouble and expense to clean the cars of all ore lodged 35 upon the same. This labor is greatly reduced by the car described.

The body bolster comprises side filling or web members 30, one on each side of the draft sill, and a bottom connecting plate or 40 chord 31, together with the web plate 2 rising from the lower portion of the bolster and provided at its upper end with flange 32 riveted to the sloping end floor plate 15. The web plate 2 extends continuously from 45 side to side of the car, and since the space between the bolster and the sloping floor plates 15 is closed at the bottom by the horizontal web girder 20 and at the sides by the side plate girders, and since the door operating 50 mechanism is partly located in this space, it is desirable to have access to the same. This I provide by means of a manhole 33 cut through the bolster web plate 2 at the central line of the car where the plate is not subjected to material shearing stresses and 55 where such hole does not materially weaken said plate. Hand holes 34 are also provided through the plate. This plate is stiffened or strengthened by means of bars, shown as 60 angle bars 35, riveted thereto. These stiffening bars project down inside of the draft sills and are riveted thereto, as shown in Fig. 4, and are supported practically on the center bearing plate 36. They project up- 65 wardly and diverge outwardly diagonally in

order to effectively take care of the stresses which come on diagonal lines. This outward divergence of the stiffening bars also provides sufficient space for the manhole 33.

Fig. 6 shows a modification of the top chord for the plate girder sides, this consisting of a Z bar riveted to the side plate, and having a portion 38 projecting inwardly and a portion 39 then projecting upwardly. In all forms the top chord projects inwardly from the side walls, thus enabling the side walls to be placed out on the lines of the maximum width of the car, so as to increase the cubical capacity of the car.

The car illustrated contains numerous other parts, but as they form no part of the invention, it is not deemed necessary to describe the same.

What I claim is:

1. A hopper car having a single central discharge opening and sloping end floor portions provided with side retaining walls which confine the lading and having the space therebetween of unreduced cross sectional area from the end of the car to the discharge 90 opening.

2. A hopper car having a large central bottom discharge opening, sloping sides extending to the edges of said discharge opening, and end sloping floor portions provided with side portions sloping upwardly transversely of the car and forming confining walls for the lading, the space between such confining walls being of unreduced cross sectional area from the ends of the car to the discharge opening. 100

3. A hopper car having a large central bottom discharge opening, sloping sides extending to the edges of said discharge opening, and sloping end floors having their side portion from a line coincident with the edges of the 105 side openings sloping upwardly transversely of the car to the side walls.

4. A hopper car having a large central bottom discharge opening, sloping sides extending to the edges of said opening, and sloping end floor portions having their side portions from a line coincident with the side edges of the discharge opening sloping upwardly transversely of the car to the side walls and at substantially the same angle as the sloping 110 sides.

5. A hopper car having a large central bottom discharge opening, sloping side hopper plates, sloping end floor plates extending to the ends of the discharge opening, said end floor plates having side portions of a width substantially equal to the sloping side hopper plates and sloping upwardly transversely of the car to the side walls thereof. 120

6. A hopper car having a central bottom discharge opening extending lengthwise of the car a greater distance than the space between the inner truck wheels, and having sloping side hopper walls and sloping end floor portions, the side portions of said slop- 125 130

ing end floor portions sloping upwardly transversely of the car to the sides of the car and forming confining walls, said side portions being of substantially the same width as the 5 sloping side hopper plates.

7. A hopper car having a central bottom discharge opening extending crosswise of the car a greater distance than the width between wheels, and having sloping side hopper walls and sloping end floor portions, the side portions of said sloping end floor portions sloping upwardly transversely of the car to the sides of the car and forming confining walls, said side portions being of substantially the same width as the sloping side 10 hopper plates.

8. A hopper car having a body provided with sloping end floor portions, a body bolster including a web plate rising from the underframe member and supporting the sloping end floor, and stiffeners secured to the web plate and extending from the draft sills diagonally upwardly and outwardly.

9. A hopper car having a body provided with a sloping end floor portion, a body bolster including a web plate rising from the underframe and supporting the sloping floor, and stiffeners secured to the web plate and supported at the lower ends over the center 25 bearing plate and extending diagonally upwardly and outwardly.

10. A hopper car having a body provided with a sloping end floor, a body bolster including a web plate rising from the underframe member and supporting the sloping floor, and stiffeners secured to the web plate and extending from the draft sills diagonally 35 upwardly and outwardly, said web plate being provided with a manhole therethrough 40 between said stiffeners.

11. A hopper car having a body comprising side plate girders, sloping end floor plates, and a body bolster including a web plate rising from the underframe and secured to the 45 side plate girders and to the sloping floor plates and having a manhole therethrough.

12. A hopper car having a body comprising side plate girders, sloping end floor plates, and a body bolster including a web plate rising from the underframe and secured to the side plate girders and to the sloping floor plates, said bolster plate being provided with a manhole at its central line and with a hand hole at the side thereof.

55 13. A hopper car having a body comprising side plate girders, sloping end floor plates, a body bolster including a web plate rising

from the underframe and secured to the side plate girders and to the sloping floor plates, and a horizontal plate secured to the top of 60 the underframe members and to the lower ends of the sloping floor plates, said bolster web plate being provided with a manhole therethrough.

14. In a hopper car, a transverse horizontal girder attached to the draft sill and to the car sides and tapering toward the outer end of the draft sill and projecting beyond the overhanging part of the body.

15. In a hopper car, a transverse horizontal girder attached to the draft sill and to the car sides and tapering toward the outer end of the draft sill and projecting beyond the overhanging part of the body, and a raised end platform covering the exposed 75 portion of said horizontal girder.

16. In a hopper car, a transverse horizontal girder attached to the draft sill and car sides and tapering toward the outer end of the draft sill and projecting beyond the 80 overhanging part of the body so as to leave open spaces at the sides, and an elevated platform covering the exposed portions of the horizontal girder.

17. In a hopper car, the combination of 85 end sills, end side sills, draft sills, a transverse horizontal girder attached to the draft sill and car sides and tapering toward the outer end of the draft sills so as to leave open spaces at the sides between the same and 90 the end and end side sills, and an elevated platform covering the portion of the horizontal girder which projects beyond the overhanging body.

18. In a hopper car, a transverse horizontal girder attached to the draft sill and car sides and tapering toward the outer end of the draft sill and projecting beyond the overhanging part of the body, an elevated platform covering the exposed portion of said 100 horizontal girder, and a ladder extending from the side of said platform to the underframe.

19. A car having its sides composed of plates of metal located substantially on the 105 lines of maximum width of the car and having at their top edges portions projecting inwardly and then upwardly.

In testimony whereof, I have hereunto set my hand.

EDGAR WEBSTER SUMMERS.
